UNITED STATES PATENT OFFICE.

DANIEL ALEFS, OF GREAT BEND, KANSAS.

VALVE-LIFTER.

1,158,618.

Specification of Letters Patent. Patented Nov. 2, 1915.

Application filed May 25, 1914. Serial No. 840,884.

To all whom it may concern:

Be it known that I, DANIEL ALEFS, a citizen of the United States, residing at Great Bend, in the county of Barton, State of Kansas, have invented certain new and useful Improvements in Valve-Lifters; and I do hereby declare the following to be a full, clear, and exact description of the invention, such as will enable others skilled in the art 10 to which it appertains to make and use the same.

This invention relates to valve lifters and has for an object to provide an extensible jaw on one of the handle levers of the valve lifter whereby the tool may be adjusted to fit various sizes of valves.

A further object is to provide a tool of this character that will be formed of a few simple parts that may be manufactured at a 20 minimum cost and that will not easily get out of order.

With the above objects in view the invention consists of certain novel details of construction and combination of parts hereinafter fully described and claimed, it being understood that various modifications may be made in the minor details of construction within the scope of the appended claim.

In the accompanying drawing illustrating 30 this invention, Figure 1 is a sectional view showing the application of the invention, the tool being in elevation. Fig. 2 is a longitudinal sectional view through the tool showing the adjustable jaw in dotted lines 35 in an adjusted position. Fig. 3 is a perspective view of the tool adjustable jaw with the cap removed. Fig. 4 is a perspective view of the cap.

Referring now to the drawing in which 40 like characters of reference designate similar parts, the tool is shown to comprise a pair of handle levers 10 and 11 crossed near their working ends and pivotally connected together at their crossing by a pivot pin 12, 45 the levers beyond their crossing being curved in opposite directions to provide jaws 13 and 14 one of which terminates in a forked working end 15 and the other of which terminates in an enlarged externally threaded head 16 50 upon which is screwed a cap 17.

The forked jaw 15 is adapted to receive the valve stem 18 and engage beneath the lower end of the valve spring 19 while the cap 17 of the jaw 13 is designed to bear upon the top of the valve 20 as shown in Fig. 1. 55 When the handle levers are compressed the valve will be held seated by the jaw 13 while the forked jaw 15 will move upwardly and compress the valve spring 19 to permit withdrawal of the usual key whereupon the valve 60 may be withdrawn for cleaning and repairs.

It is well known that in various types of engines the valves are disposed at various distances below the top of the valve chambers, and it will be seen that the jaw 13 of 65 this tool is extensible to adapt the tool to be applied to valves disposed at various distances below the top of the respective valve chamber. By simply retracting or advancing the cap 17 on the threaded head 16 the 70 jaw 13 may be adjusted as above described and for the purpose above described.

From the above description it will be seen that I have provided an extremely simple and durable valve lifter that will be formed 75 of a few strong and durable parts that will be effective in operation and will not easily get out of order.

What is claimed, is:—

A device for compressing valve springs 80 consisting of crossed levers pivoted together at their point of intersection, the said levers terminating at one side of their pivotal point in handles and at the other side of their pivotal point in oppositely extending 85 arcuate jaws, the free ends of one of the jaws being threaded and having a sleeve adjustably mounted thereon whereby the jaw may be accommodated to valve chambers of various depths, the free end of the other jaw 90 terminating in an outwardly bent bifurcated portion.

In testimony whereof, I affix my signature, in the presence of two witnesses.

DANIEL ALEFS.
